UNITED STATES PATENT OFFICE.

FAY H. WEBSTER, OF MARVELL, ARKANSAS

STREET-INDICATOR FOR CARS.

1,093,508.

Specification of Letters Patent. Patented Apr. 14, 1914.

Application filed June 17, 1913. Serial No. 774,188.

To all whom it may concern:

Be it known that I, FAY H. WEBSTER, a citizen of the United States, and a resident of Marvell, in the county of Phillips and 5 State of Arkansas, have made certain new and useful Improvements in Street-Indicators for Cars, of which the following is a specification.

My invention relates to street indicators, 10 and more particularly to street indicators carried upon cars for the purpose of disclosing, to persons occupying the cars, the names of the streets, in successive order, as the car travels along.

15 More particularly stated, my invention comprehends an indicator having a band or ribbon upon which the names of the streets are successively displayed, and improved mechanism for actuating this ribbon 20 or band step by step.

My invention further comprehends means for enabling the indicating mechanism to automatically make allowance for streets, the names of which are not intended to be 25 displayed, the indicator mechanism being so arranged that when a car passes a street, the name of which is not to be displayed, such name will be practically skipped, though the name in question may be carried 30 by the ribbon or band.

My invention further contemplates mechanism for automatically reversing the direction of step by step travel of the indicating mechanism whenever the car reaches the 35 end of the route and starts upon its return trip.

My invention also comprehends mechanism for enabling the name ribbon to be virtually lengthened or shortened in order 40 to adapt the apparatus as a whole for service upon either long or short routes with a minimum of time and trouble to the operator.

My invention comprises, in addition, a 45 number of improvements for increasing the efficiency of indicator mechanisms of the class to which this one relates.

Other objects sought to be accomplished by 50 my invention will appear as hereinafter described, and in connection with the detailed description.

In the accompanying drawings forming a 55 part of this specification, and in which like letters indicate like parts, I disclose one representative form of my invention.

Figure 1 is a front elevation or face view

of the indicator mechanism, certain parts being broken away. Fig. 2 is a side view, partly in elevation and partly broken away, of the mechanism shown in Fig. 1, and showing the mechanism as it would appear to a person standing at the left of Fig. 1. Fig. 3 is a fragmentary side view, partly in elevation and partly broken away, showing the indicator mechanism as seen from a point at the right of Fig. 1. Fig. 4 is a detail showing, in fragmentary side elevation, the trolley wheel and parts adjacent thereto for supplying current to the car and to the indicating mechanism. Fig. 5 is a fragmentary vertical section through the trolley wire and showing the same parts as Fig. 4. Fig. 6 is a detail showing, partly in elevation and partly in section, a part of the step by step actuating mechanism, and means for periodically locking the indicator against excessive movement. Fig. 7 is a detail showing partly in plan and partly in section the locking mechanism just mentioned. Fig. 8 is a diagram showing the mechanism of the reversing switch for the indicator mechanism. Fig. 9 is a detail showing a switch used in connection with the mechanism for causing the street names to be practically skipped. Fig. 10 shows a group of electric switch mechanisms used for the purpose of automatically shifting the various circuits during the operation of the indicator mechanism. Fig. 11 is a side elevation showing a form of indicator mechanism in which provision is made for lengthening or shortening the name ribbon. Fig. 12 is a diagram of the wiring. Fig. 13 is a fragmentary section on the line 13—13 of Fig. 2, looking in the direction of the arrow.

The indicator casing is shown at 13 and is provided with a window 14 through which legends indicating the street designations may be observed. Secured to the casing is a framework 15 for supporting various parts. Two drums are shown at 16, 17, and connected with these drums are gear wheels 18, 19. The drums and gear wheels are mounted rigidly upon two horizontally disposed shafts 20, 21, the latter being journaled relatively to the framework.

Mounted rigidly upon the shaft 21 is a wheel 22 provided with radially disposed stop pins 23. Two sprocket chains 24, 25, are mounted upon the gear wheels 18, 19, and are located in planes parallel to each other. Guide rollers 26 are disposed adja-

cent to the chains for preventing them from unduly sagging, as well as from being thrown out of position. The name ribbon is shown at 27, its edges being secured to 5 the sprocket chains 24, 25. The name ribbon carries legends indicating the street numbers as shown in Fig. 1—the particular street here indicated being 110 St. W.

Mounted upon the sprocket chain 24 is an 10 arm 28 extending laterally a short distance from the chain as indicated by dotted lines from Fig. 1. This arm has a general arcuate form for the purpose of enabling it to pass certain parts without disturbing them, 15 as hereinafter described.

Another arm 29 is mounted upon the chain 24, but is shorter than the arm 28. Both of these arms, together with an arm 30 shown in dotted lines in Fig. 1, and substantially 20 similar to the arm 28, are used for the purpose of tripping certain switch levers as described below.

Mounted within the casing 13 are two solenoids 31, 32, disposed in axial alinement 25 with each other, and an armature 33 is common to these two solenoids. Two other solenoids 34, 35, are similarly provided with an armature 36. The armatures 36, 33, are mounted upon two swinging arms 37, 38, 30 the latter being supported upon leaf springs 39, 40, and loosely connected with the armatures by pins 41.

Mounted within the casing and disposed adjacent to the arm 37 is a lock 41, the form 35 of which may be understood from Figs. 6 and 7. This lock is provided with a slideway 42 and fitted into this slideway is a slide 43 provided with an opening 44 and with a bevel face 45 partially bounding this 40 opening. The slide is further provided with a bolt 46 which extends outwardly from the lock.

Two spiral springs 47 are mounted within the lock 41 and disposed upon opposite 45 sides of the bolt. These springs engage the slide 43 and normally press the same toward the left according to Fig. 7. The arm 37 carries a pawl 40^a for entering the opening 44 and engaging the bevel face 45, so that 50 when the arm 37 descends to its limit, the bolt 46 is forced to the right. The arm 37 carries a finger 38^a and engaging this finger is a spring 39^a. The finger 38 is pivotally supported upon the arm 37 and is adapted 55 to swing angularly in one direction against the tension of the spring 39^a. By this arrangement, the finger 38 is adapted to bend sufficiently to pass any one of the pins 23 which happens to lie in its path of travel, 60 and when the arm 37 is drawn downwardly it engages a pin 23 and thus turns the wheel 22 to a distance representing the space between consecutive pins 23.

Each time the arm 37 descends so as to 65 cause the movement of the wheel 22, as just

described, the bolt 46 is thrust outwardly toward the right according to Figs. 6, 7, the pin being thus securely locked between the finger 38^a and the bolt 46. This prevents excessive travel of the wheel 22 and 70 renders positive the step by step movements of this wheel and parts driven thereby.

Another lock 48 similar in all respects to the lock 41, is provided, as shown in Fig. 2, and located upon the side of the wheel 22 75 opposite the lock 41. The arm 38 is provided with a finger 38^a and a pawl 48^a like those carried by the arm 37.

Two switch arms 49, 50, constructed alike, are used in connection with the arms 37, 38. 80 The arm 49 is shown more particularly in Fig. 10. It is mounted upon a stationary shaft 51, the latter being supported rigidly upon the casing. Each switch arm 49, 50, is provided with laterally extending portions 52 integral with it, and between these laterally extending portions are the arms 37, 38. Whenever either arm 37, 38, is depressed, it causes the corresponding switch arm 49 or 50 to rock, and when the arm 37 or 38 is moved back into its normal position, the switch arm 49 or 50 is by its aid restored to normal position. Adjacent the lower end of each switch arm 49, 50, is a contact 53, which is normally open, but is 85 adapted to be closed by the rocking of the switch arm, as may be understood from Fig. 10.

Located above each switch arm 49, 50, is a yoke 54 journaled upon a pin 55 and provided with a counter-balance 56 for holding the yoke in either of two extreme positions into which it may be moved, as indicated by dotted and full lines in Fig. 10.

Each yoke 54 is provided with two ends 57, 58, disposed upon opposite sides of the upper end of the switch arm 49 or 50, so that the yoke may be readily rocked by movements of the switch arm. Each yoke 54 carries a switch blade 59 which is insulated from the body portion of the yoke by means of insulation 58^a. Located adjacent each yoke 54 are two contact members 60, 61, so arranged as to be readily engaged or disengaged when the yoke is rocked. Each switch arm 49, 50, carries a contact button 62, and adjacent to this contact button is a contact spring 63, these parts being so arranged that when the switch arm moves into its normal position the contact button 62 lodges against the contact spring 63. A lever arm 64 is journaled upon a shaft 65 and carries two contact members 66, 67, and an insulating member 68 for preventing leakage of current from the contact member. Mounted adjacent the switch arm 64 are contact sectors 69, 70, which are separated from each other by a sector 71 of insulating material. Two other contact sectors 72, 73 are provided and are separated by a sector 74 105 110 115 120 125 130 135 140 145 150 155 160 165 170 175 180

of insulating material. Located concentrically to the various sectors just mentioned are two other contact sectors 75, 76, the latter being always in engagement with the respective contact members 66, 67. The lever arm 64 is secured rigidly upon the shaft 65 and is adapted to cause the same to rock. Two other lever arms 77, 78, are journaled loosely upon this shaft and are adapted to be rocked independently of movements of the shaft and also independently of movements of each other. The lever arm 77 carries a contact member 79, and the lever arm 78 carries a similar contact arm 80. Adjacent the contact member 79 are two contact sectors 81, 82, separated by a sector 83 of insulating material.

Adjacent the contact member 80 are two contact sectors 84, 85, separated by a sector 86 of insulating material. Connected with the contact sectors 79, 80 are two armatures 79^a, 80^a, and these armatures extend into two solenoids 87, 88.

The trolley pole carried by the car is shown at 89, the trolley wheel at 90 and a portion of the trolley wire at 91. Mounted at each street intersection is a tripper 92 carried by the trolley wire, and provided with a laterally extending arm 93, the latter carrying at its outer end a hook 94 extending slightly inward or toward the wire, as may be understood from Fig. 5. The trolley pole 89 is journaled upon a trolley pedestal 95 carried by the car. This pedestal is provided with a laterally extending arm 96 which carries two contact posts 97, 98, the latter being supported from the arm 96 by aid of an insulator 99.

Carried by the car and concentric to the trolley pedestal 95 are contact sectors 100, 101, 102, 103, each having the proximate form of a semicircle. The sectors 100, 101, 102, 103 are insulated by short sectors 100^a of insulating material. Connected with the sector 101 is a wire 104. A wire 105 is connected with the sector 103. These two wires are connected to a wire 106 which leads to the sector 75. A wire 107^a is connected to the sector 100. Another wire 108^a is similarly connected to the sector 102. These two wires are connected to a wire 109 which leads to the sector 76. A wire 110 is connected with the sector 72 and with a wire 111, the latter leading to the sector 69. The wires 110, 111, 55 are connected to a wire 112. A wire 113 extends from the wire 112 to a push button 114 and from the latter wires 115, 116, lead to the sector 81. Connected with the wires 115, 116, is a wire 117 which leads to a distributing post 118. A wire 119 leads from this distributing post to the trolley pedestal 95. Another wire 120 leads from the distributing post 118 to the solenoid 87. Connected with the respective sectors 73, 70, are two wires 121, 122. Connected with these wires

is a wire 123. This wire is connected with a wire 124, the latter being in turn connected with a wire 125 leading to the solenoid 35. A wire 126 is connected with the wires 124 and 125, and leads to the pin 51 upon which the switch arm 50 is supported. A wire 127 leads from the solenoid 35 to the ground 132. A wire 128 is connected with the distributing post 118 and also with a wire 129, the latter leading to the solenoid 31. From this solenoid a wire 130 leads to the contact member 60, associated with the switch arm 49. A wire 131 leads from the contact member 61 to the ground 132. By aid of a wire 133 the solenoid 87 is in metallic communication with the contact 53, the latter being connected to the ground 132 by a wire 132^a. Connected with the wires 112, 113 is a wire 134, the latter being in metallic communication with the solenoid 32. This solenoid is in communication with the ground 132 by a wire 132^b. Connected with the wire 134 is a wire 135 which leads to the pin 51 serving as a support for the switch arm 49. Connected with the contact member 63 is a wire 136 which leads to the sector 82. A wire 137 leads from the distributing post 118 to a push button 138. Connected with the latter is a wire 139 which is also connected with the wires 123, 124.

A wire 140 is connected with the wires 128, 129, and leads therefrom to the solenoid 34. A wire 141 leads from this solenoid to the contact member 60 associated with the switch arm 50. A wire 142 leads from the contact member 61, associated with the switch arm 50, to the ground 132. A wire 143 extends from the sector 85 to the contact member 63 associated with the switch arm 50. Connected with the solenoid 88 is a wire 144 which leads to the contact 53 associated with the switch arm 50. From this contact a wire 145 leads to the ground 132. A wire 147 leads from the distributing post 118 to the solenoid 88. Another wire 148 leads from the distributing post 118 to the sector 84. Mounted upon the upper end of the trolley pole 89 is a lever 149 and engaging opposite sides of this lever are pins 150. Pressing against these pins are springs 151, the pins and springs being carried by housings 152 so as to normally maintain the lever 149 in a predetermined central position, but free to be moved slightly in either of two directions when actuated by a force sufficient to compress either of the springs. The lever 149 is journaled upon a pin 153 which also serves as an axle carrying the trolley wheel 90. The lever 149 is provided with an upwardly extending lug 154 integral with it, this lug being so positioned as to readily engage the inwardly extending portion 94 of the trip, as will be understood from Figs. 4 and 5.

The trolley wheel 90, lever 149 and vari-

ous other parts immediately associated with these parts are carried upon a trolley harp 155. Two contact members 105^a, 106^a are insulated from each other and from the trolley harp. These contact members preferably have the form of spring tongues, as indicated in Fig. 4. These contact members are connected respectively to the wires 107, 108.

10 In Fig. 11 I show a slightly different arrangement of the mechanism. The casing appears at 156, and the framework at 157. There are two sprocket chains, one of them appearing at 158. These two sprocket 15 chains each have a depending middle portion 158^a engaged by a sprocket wheel 159. There are two of these sprocket wheels which support a roller 160 by aid of a shaft 161. This shaft extends through vertical 20 slots in the framework, one of them being shown at 162. The purpose of this arrangement is to enable sprocket chains of different lengths to be employed, the difference in length being compensated by the position assumed by the roller 160. The weight of this roller rests upon the sprocket chains. By thus having sprocket chains of different lengths, the indicator mechanism may be accommodated to differences in the number 25 of street names employed. In other words, the name ribbons may be long or short.

Except as just indicated, the indicator mechanism shown in Fig. 11 is like the indicator mechanism shown in Figs. 1, 2, and 3. The arm 29 is of proper length to engage the switch arm 64 so as to swing this switch arm into its reverse position, and the arm 28 is of greater length (see Fig. 1) in order to engage the switch arm 77 and shift 30 the position of the latter. Any desired number of arms 28 may be placed upon the chain 24, though usually a single arm of the kind shown at 29 is sufficient. The chain 25 may similarly be provided with any desired number of the arms 30.

When the car travels in one direction along the route, the indicator mechanism is actuated step by step in one direction, but when the car reaches the end of the route, 35 turns around and travels back over the same route, the indicator mechanism travels step by step in the direction contrary to which it first traveled, the reversal being brought about by the action of the arm 29 upon the switch arm 64.

The shaft 65 carries a head 88^b, whereby it may be turned by hand, as will be understood from Fig. 1. By turning the shaft by hand, the reversing switch (shown more particularly in Fig. 8) can be shifted independently of movement of the car.

The operation of my device is as follows: I will suppose that the car is traveling to the right according to Fig. 12, and that the 60 normal direction of travel of the rotary

parts of the indicator mechanism is clockwise according to Fig. 2. The contact lever 149 is now out of engagement with each of the contact members 105^a, 106^a, and all of the circuits immediately associated with the indicator mechanism are open. The car reaches one of the trippers 92, or in other words, arrives at a street, the name of which is to be displayed. The upwardly extending portion 154 of the contact lever now engages the portion 94 of the tripper so that the contact lever 149 is turned slightly in a counter-clockwise direction according to Fig. 12, and thus brought into engagement with the contact member 105^a. The following circuit is thus completed: source of supply (say a power house), trolley wire 91, trolley wheel 90, contact members 149, 105^a, wire 107, arm 97, sector 102, wires 108^a, 109, contact members 66, 72, wires 110, 112, 114, solenoid 32, wire 132^b to ground 132, thence back to source of supply. This energizes the solenoid 32, causing the switch arm 49 to rock in a clockwise direction according to Fig. 12. This rocks the yoke 54 in a counter-clockwise direction and causes the contact blade 59 to engage the contact springs 60, 61. This movement of the yoke 54, however, does not take place until the switch arm 49 reaches the limit of its rocking movement so that the armature 33 reaches its proximate lowest position. The engagement of the contact blade 59 with the contact springs 60, 61, completes the following circuit: power house, trolley wire 91, trolley 100 wheel 90, trolley pole 89, trolley pedestal 95, wire 119, distributing post 118, wires 128, 129, solenoid 31, wire 130, contact members 60, 59, 61, wire 131 to ground 132, thence back to power house. This energizes the 105 solenoid 31, this step occurring a moment later than that in which the solenoid 32 is energized. The effect of energizing the solenoid 31 is to restore the switch arm 49 to its normal position, and in so doing to cause it 110 to rock the yoke 54 so that the contact blade 59 moves out of engagement with the contact members 60, 61. The armature 33 suddenly descends and immediately rises. This movement causes the arm 38 to dip downwardly and to return to its normal position so that the wheel 22 is turned one step in a clockwise direction according to Fig. 2. The shaft 21 and parts carried by it being turned 115 in the same way, the chains 24, 25, are actuated and the name ribbon 27 is moved one step—that is, a distance sufficient to remove a legend from the window 14 and display the next successive legend—indicating, as above explained, a street designation. The 120 rocking movement of the switch arm 49 moves the contact member 62 out of engagement with the contact member 63, this movement, however, being virtually idle as the circuit controlled by these contact mem- 125

bers is now open. The rocking of the switch arm 49 also closes and opens the contact 53. The following circuit is thus momentarily completed: power house, trolley wire 91, trolley wheel 90, trolley pole 89, pedestal 95, wire 119, distributing post 118, wire 120, solenoid 87, wire 133, contacts 53, wire 132^a, ground 132, back to power house. This energizes the solenoid 87 and insures that the contact member 79 is out of engagement with the sectors 81, 82. The solenoid 87 being of high-resistance, the waste of current from repeatedly energizing the solenoid is negligible. As each successive street (represented by a tripper 92) is reached, the name ribbon is actuated one step. It may happen, however, that for some reason the operator does not desire a particular street name to be indicated, when the car passes or crosses the street bearing the name in question. In other words, the operator may want the indicating mechanism to skip the name of a particular street when that street is reached. This is accomplished by securing an arm 28 upon the sprocket chain 24 for each street the designation of which is to be skipped. The location of the arm 28 determines the particular street name to be skipped and the number of such arms governs the number of such names to be thus affected.

I will now suppose that a street of the kind just mentioned is reached by the car and that such street is duly represented by a tripper 92. Also that the arm 28 has been properly positioned, before the beginning of the trip, for the purpose of causing the indicator mechanism to make the desired skip. As the trolley wheel passes the tripper 92, two circuits through the solenoids 31 and 32, are each completed in succession, as above explained, but the instant the arm 49 is restored to its normal position, the arm 28 carried by the sprocket chain 24 moves the switch lever 77 into such position that the contact plate 79 engages both of the adjacent contact sectors 81 and 82. This being done the restoration of the switch arm 49 to its normal position causes the contact member 62 to engage the contact member 63, the result being that the following circuit is completed: power house, trolley wire 91, trolley wheel 90, trolley pole 89, pedestal 95, wire 119, distributing post 118, wires 117, 116, contact members 81, 79, 82, wire 136, contact members 63, 62, switch arm 49, wire 135, solenoid 82, wire 132^b, to ground 132, thence back to power house. This energizes the solenoid 82 and thus causes the switch arm 49 to rock in a clockwise direction so as to actuate the yoke 54, causing the switch blade 59 to engage the contact members 60 and 31 and by so doing complete a circuit through the solenoid 31, as above described with reference to the action of the yoke 54 when restored to its normal position. It will thus

be seen that upon reaching the street the designation of which is to be skipped, the solenoids 32, 31, are actuated twice in rapid succession so that the switch arm 49 makes two complete movements and is twice in 70 succession restored to normal position. This means that the sprocket chains and the name ribbon carried by them are all moved two steps in rapid succession. The result is that the name of the street is displayed for an instant,—the fraction of a second,—and moved out of the way, another name taking its place and rendered visible through the window 14.

In practice the momentary display of the name, as described, merely amounts to the 80 flickering and unintelligible display of the street designation. The pressure of the arm 28 upon the lever 77 for the purpose of turning this lever is greater than the pull of the armature 79^a under attraction of the solenoid 87, so that the momentary energizing of the solenoid 87, due to closure of the contact 53 by the rocking of the switch arm 49, does not prevent the movement of the lever 77 for the purpose of bringing the contact 90 plates 79 into engagement with the sectors 81, 82, as above described. As soon, however, as the arm 28 passes the contact lever 77, after shifting this lever, the solenoid 87 restores the lever 77 to its normal position. 95 This is due to the fact that during the second complete rocking movement of the contact lever 49, as just described, the contact 53 is momentarily closed, while the contact plate 79 is still in engagement with the sectors 81, 82. The following circuit is thus completed: power house, trolley wire 91, trolley wheel 90, trolley pole 89, pedestal 95, wire 119, distributing post 118, wire 120, solenoid 87, wire 133, contact 53, wire 132^a, 105 ground 132 to power house. This energizes the solenoid 87 and shifts the contact lever 77 back into its normal position.

I find it convenient to arrange one or more arms 28 upon the sprocket chain 24, and 110 adapt it for use while the car is traveling along the route in one direction, and to place one or more arms 30, similar to the arm 28, upon the sprocket chain 25 and adapt it for use while the car is traveling along the route 115 in the reverse direction.

I will now explain how the direction of the step by step movement of the indicator mechanism is reversed when the car reaches the end of the route and turns around in order to go back over the route the mechanism of the car, however, being arranged so that, relatively to the car, the movement is always progressively ahead. The arm 29 is so located upon the chain 24 that when the car reaches the end of the route this arm 29 is brought against the contact lever 64 so as to shift the same in a clockwise direction according to Fig. 12. In shifting the contact lever 64, the contact plate 66 disengages the 120

sector 72 and engages the sector 73, its connection with the sector 76, however, being maintained. Similarly, the plate 67 disengages the sector 70 and engages the sector 69, but does not move out of engagement with the sector 75. I will further suppose that the trolley pole 89 is not to be reversed relatively to the car—not to be swung around so as to trail behind. This is usually the case where the car follows a loop around, and therefore virtually travels continuously ahead. In this event, the indicator mechanism must be made to display the street names in the reverse order to that in which they were first displayed. When the trolley wheel 90 passes a tripper 92, the rocking of the switch arm 149 brings this switch arm into engagement with the contact member 105^a. This completes the following circuit: power house, trolley wire 91, trolley wheel 90, switch arm 149, contact member 105^a, wire 107, contact post 97, sector 102, wires 108^a, 109, sector 76, contact plate 66, sector 73, wires 121, 123, 124, 125, solenoid 35, wire 127 to ground, thence back to power house. This energizes the solenoid 35, causes the armature 36 to descend and rocks the switch arm 50 in a counter-clockwise direction according to Fig. 12. This causes the yoke 54 associated with the contact arm 50 to rock, and thus bring the contact blade 59 of this yoke into engagement with the contact members 60, 61. The engagement of the contact blade 59 with the contact member 60, 61, completes a circuit through the solenoid 34 so that the armature 36 is drawn quickly upward, the switch arm 50 being thus rocked back into its normal position. The performance of the switch arm 50 is exactly like that of the switch arm 49 with the exception that the solenoids 35, 34 and 88 are energized instead of the solenoids 32, 31 and 87. The rocking of the switch arm 50 causes the indicating mechanism to display the names of the streets, but in reverse order, as above described. Whenever the arm 30 carried by the sprocket chain 25 engages the lever arm 78, so as to shift the position of this lever arm, a street designation is practically skipped, as above described with reference to the action of the switch arm 77.

If the route of the car does not end in a loop, or if for any reason it is desirable to merely swing the trolley pole 89 around so as to cause the car to virtually travel backward upon the return trip, the arm 29, used for shifting the position of the switch arm 64, may remain idle. This means that the switch arm 64 is not to be shifted. Under such conditions the reversal of the indicator mechanism takes place as before, but is due merely to shifting the position of the trolley pole 89 so that the contact posts 97, 98, disengage the sectors 102, 103, and engage the sectors 101, 100.

If for any reason the operator desires to actuate the indicator mechanism independently of movements of the car, he does so by closing the push button 114 or 138, depending upon the direction of travel of the car. Assuming that he presses the push button 114, the following circuit is completed: power house, trolley wire 91, trolley wheel 90, trolley pole 89, pedestal 95, wire 119, distributing post 118, wires 117, 115, push button 114, wires 113, 134, solenoid 32, wire 132^b, ground 132, to power house. This energizes the solenoid 32 and causes the switch arm 49 to rock. The rocking of the switch arm 49 causes the adjacent yoke 54 to rock and close a circuit through the contact blade 59, contact members 60, 61 and solenoid 31. Similarly, if the car be traveling in the reverse direction, closing the push button 138 energizes the solenoid 35 and rocks the switch arm 50. This rocks the yoke 58, and the contact blade 59 completes a circuit through the solenoid 34. The operator, therefore, by pressing upon either push button 114 or 138, may advance or set back the name ribbon one step for each push of the button.

The operator by grasping the head 88^b (see Fig. 1) can turn the shaft 65 so as to shift the switch arm 64 and thus reverse the direction of relative movement of the indicator mechanism. With the mechanism shown in Fig. 11, the action is the same as above described with the exception that the name ribbon may be changed as to its virtual length so as to increase or diminish the number of streets, the names of which are to be displayed.

I do not limit myself to the precise arrangement shown as variations may be made in the construction without departing from the spirit of my invention.

I claim:—

1. A street indicator for cars comprising revolute drums, a name ribbon mounted thereupon and provided with legends for displaying the designations of streets, mechanism for actuating one of said drums step by step so as to display said legends one at a time in a definite order of succession, and means for causing said step by step mechanism, to quickly withdraw a legend after displaying the same so as to prevent said legend from making an effective indication.

2. A street indicator for cars comprising indicator mechanism movable step by step, means for actuating said mechanism and for stopping the same after each successive actuation thereof, mechanism controllable by progress of the car for reversing the direction of travel of said indicator mechanism relatively to the car upon reaching the end of the route, and means for preventing the indicating mechanism from effectively

making a predetermined indication along the route.

3. A device of the character described comprising a rocking arm, a pair of solenoids connected with said rocking arm and adapted to be energized at different moments for rocking said arm into and out of a predetermined normal position, means controllable by movements of a car for energizing one of said solenoids, mechanism controllable by the shifting of said rocking arm for energizing the other solenoid, and indicator mechanism controllable by said solenoids and movable step by step for displaying legends indicating street designations.

4. A device of the character described comprising a rocking arm, a pair of sole-

noids connected with said rocking arm and adapted to be energized at different moments for rocking said arm into and out of a predetermined normal position, means controllable by movements of a car for energizing one of said solenoids, mechanism controllable by the shifting of said rocking arm for energizing the other solenoid, indicator mechanism controllable by said solenoids and movable step by step for displaying legends indicating street designations, and mechanism controllable by said solenoids for periodically holding and releasing said indicator mechanism.
